UNITED STATES PATENT OFFICE.

JOHN P. KYLE, OF AREDALE, IOWA.

WAGON-BOX ATTACHMENT.

1,250,326.

Specification of Letters Patent. Patented Dec. 18, 1917.

Application filed November 22, 1915. Serial No. 62,823.

To all whom it may concern:

Be it known that I, JOHN P. KYLE, a citizen of the United States, residing at Aredale, in the county of Butler, State of Iowa, have invented certain new and useful Improvements in Wagon-Box Attachments; and I do hereby declare the following to be a full, clear, and exact description of the invention, such as will enable others skilled 10 in the art to which it appertains to make and use the same.

My invention relates to wagon box attaching or locking devices and the objects thereof, resides in the provision of means 15 for detachably securing an auxiliary box or rack to the ordinary box of a wagon.

The invention further contemplates a device of the character aforesaid which is easy and efficient in operation and which will 20 prevent the rattling of the upper box or rack, and prevent in a measure the warping or bulging of same.

The invention consists of the novel features, details of construction, and combination of parts, which hereinafter will be 25 more particularly set forth, illustrated in the accompanying drawings, and pointed out in the appended claims.

Referring to the drawings forming a part 30 of the application,

Figure 1, is a side elevation of a portion of a wagon box and the auxiliary box, showing the application of my improved locking device thereto.

Fig. 2, is a section of the boxes on line 35 2-2 of Fig. 1, showing one of my devices in elevation.

Fig. 3, is a detail view of the latch mechanism with a portion of the tension spring 40 attached thereto.

Fig. 4, is a detail view of the hook element, and

Fig. 5, is a sectional view.

Corresponding and like parts are referred 45 to in the following description and indicated in all the views of the drawings, by the same reference characters.

Referring now to the drawings, the numeral 5, designates the body or box of a 50 wagon comprising the usual construction, and having a plurality of cleats 6, adapted for the reception of the standards 7, on the sides of the auxiliary box or rack 8, by which the latter is supported on the lower 55 box 5.

As is well known, the upper box or rack

by its loose mounting on the lower box, has a tendency to excessively rattle and upon the wagon encountering very rough or uneven roads, may become detached from the lower 60 box and this objection is obviated by my improved locking device, which comprises the latch and hook elements A and B.

The latch element A comprises a shoe or plate 9, having an opening 9' for a screw 65 10, and a lower opening 9'' for the reception of a bolt 11, whereby it is secured to the upper box body 8, and being disposed at an angle thereon. The box body 8, is provided with an opening for the passage of the bolt 70 11, therethrough, and has one end terminating in a circular recess. A collar 11' is mounted in the lower opening 9'', of the latch element and has a portion seated in the circular recess of the box body. The bolt 75 11, passes through the collar 11' and a washer is positioned between the bolt head and the lower end of the plate 9. By this arrangement by tightening up the screw on the end of the bolt which projects within 80 the box body, the parts are held in position.

A lever 12, has its lower end offset to form a bearing 13, which latter is apertured at 14, for the reception of the collar 11', and the bolt 11, constituting its pivotal mounting 85 on the plate 9. The opposite end of the lever 12, terminates in a cylindrical pointed shank portion 15, adapted to be received by the bent over portion or hook 16, on the upper end of the plate 9, when the device 90 is in locked position. Intermediate the ends, the lever 12, is provided with an outwardly bent portion 17, to provide clearance over the bolt 11, for the link 18, which is pivotally mounted on a pin 19, in the outwardly bent 95 portion 17 of the lever. The link 18 is provided with an eye 20, which is permanently attached to the helical spring 21, while the opposite end of the spring is detachably connected to the hook 22, of the element B, 100 on the lower wagon box.

The spring 21 tends to pull the lever 12 downwardly, thereby relieving its tension, but when the lever 12 is carried upwardly and to the left (Fig. 3), the spring 21 is 105 tensioned until the lever is carried past the vertical line through the bolt 11, when it is snapped into locking engagement with the hook 16. The link 18, obviously, swings in the line of tension of the spring 21, and when the lever 12 stands in locked position, the link 18 extends downwardly upon the 110

corresponding side of the bolt 11, the parts holding this position until the lever 12 is again swung to the right past the vertical line through the bolt 11.

5 It will thus be seen that the upper box or track will permanently carry the locking element A, while the lower box carries the hook element B, and any movement of the upper box relative to the lower box will be taken up by the spring 21, which serves to hold the bodies against vertical movement.

10 It is therefore obvious that all vibration and rattling encountered by the bodies will be in a great measure minimized and the said upper box is securely locked on the lower box, the locking elements being permanently carried by the respective boxes, and preventing the loss, or displacement of same. Likewise by the peculiar construction and mounting of the lever 12, on the plate 9, the collar 11, forms a bearing for the said lever around which it may operate without the danger of the lever becoming loosely hung through the rotation of the bolt 11.

15 25 From the foregoing description, taken in connection with the accompanying drawing, the advantages of construction and the method of operation will be readily apparent to those skilled in the art to which the invention appertains. While I have described the principle of operation of the invention together with the device which I now consider the embodiment thereof, I desire to have it understood that such changes may 30 be made as are desired, within the scopes of 35 the claims appended hereto.

What is claimed is:—

1. A wagon box fastener comprising in 40 combination, a base plate adapted to be secured to a wagon box, said base plate having a bearing formed at its lower end, a

locking device formed at its upper end, a lever pivoted upon the bearing and shaped to engage with the locking device, a link pivotally carried by the lever at an intermediate point on the latter, a spring mounted on the free end of the link, and a hook adapted to be secured to a second wagon box for engagement by the opposite end of the spring, said hook being placed out of alignment with the locking device and bearing and said locking device being adapted to catch the lever when the latter is carried past the point of alignment of the link and lever which determines the instant of maximum tension of the spring.

2. A locking device for wagon boxes, comprising in combination, a base plate adapted to be carried by a wagon box, a lever mounted on one end of the base plate, a bearing for said lever, a locking device located at the opposite end of the base plate, a spring pivotally carried by the lever, and a hook adapted to be carried by a second wagon box in position to be removably engaged by the opposite end of said spring, said lever being adapted to be snapped into engagement with said locking device by said spring when it is carried past the line through the hook and bearing, said bearing consisting of 60 a tubular sleeve passed through the base plate and into the wagon box, a bearing bolt passed therethrough, and a plate interposed between the head of the bolt and said sleeve, said sleeve being projected beyond the base 65 plate to support said lever.

In testimony whereof, I affix my signature, in the presence of two witnesses.

JOHN P. KYLE.
